US00D777026S

(12) **United States Design Patent** (10) **Patent No.:** **US D777,026 S**
(45) **Date of Patent:** **** Jan. 24, 2017**

(54) **PACKAGE**

(71) Applicant: **CLEAR LAM PACKAGING, INC.**,
Elk Grove Village, IL (US)

(72) Inventors: **James J. Sanfilippo**, Barrington Hills,
IL (US); **Milorad Radenovic**, Chicago,
IL (US)

(73) Assignee: **CLEAR LAM PACKAGING, INC.**,
Elk Grove Village, IL (US)

(**) Term: **14 Years**

(21) Appl. No.: **29/472,436**

(22) Filed: **Nov. 12, 2013**

(51) LOC (10) Cl. **09-03**

(52) U.S. Cl.

USPC **D9/416**

(58) **Field of Classification Search**

USPC D11/95, 99; D5/20, 63; D9/414, 415,

Primary Examiner — Robert M Spear*Assistant Examiner* — Marissa J Cash(74) *Attorney, Agent, or Firm* — Marshall, Gerstein & Borun LLP(57) **CLAIM**

The ornamental design for a package, as shown and described.

DESCRIPTION

FIG. 1 is a front, back-side, and top isometric view of a package that has the design, showing the lid in an open position.

FIG. 2 is a top plan view of the package showing the lid in the open position.

FIG. 3 is a front, back-side, and top plan view of the package showing the lid in a closed position.

FIG. 4 is a top plan view of the package showing the lid in a closed.

FIG. 5 is a front elevation view of the package. The rear elevation is the same.

FIG. 6 is a side elevation view of the package. The opposite side elevation view is a minor image of this view.

FIG. 7 is a bottom plan view of the package.

FIG. 8 is a front, back-side, and top isometric view of a package that has a second embodiment of the design, showing the lid in an open position.

FIG. 9 is a front elevation view of the package showing the lid in the open position.

FIG. 10 is a front, back-side, and top isometric view of the package that has the second embodiment of the design, showing the lid in a closed position.

FIG. 11 is a front elevation view of the package showing the lid in the closed position.

FIG. 12 is a rear elevation view of the package.

FIG. 13 is a top plan view of the package. The bottom plan view is the same; and,

FIG. 14 is a side elevation view of the package. The opposite side elevation view is a minor image of this view.

The dashed lines show elements of the package that form no part of the claimed design. The dash-dot lines show the boundary of the claimed design, and form no part of the claimed design.
